UNITED STATES PATENT OFFICE

HARRY E. HICKS, OF PALMYRA, NEW JERSEY, ASSIGNOR TO ACME STAPLE COMPANY, OF CAMDEN, NEW JERSEY, A CORPORATION OF NEW JERSEY

STAPLE SETTING MACHINE

Application filed June 29, 1931. Serial No. 547,538.

This invention relates to improvements in staple setting machines and has for its object to provide a novel, simple and efficient means whereby a staple may be so set with relation to the work acted upon that it will not cut or punch its way through the work but will surround and enclose the entire body thereof.

The invention is particularly adapted for use in banding or bundling or binding together articles of various kinds and of varying degrees of hardness and softness.

With the object above set forth and related objects in view, the invention resides in the elements and the combinations of them hereinabove described and claimed.

In the accompanying drawings, illustrating the invention,

Figure 1 is a side view, partly broken away, of a staple setting machine embodying my invention.

Figure 2 is a front view thereof.

Figure 3 is a vertical section through the forward portion of the machine, on line 3—3 of Fig. 2, showing the member which carries the staples and the staple driver moved down into contact with the work positioning pins.

Figure 4 is a vertical section through the parts shown in Fig. 3, on line 4—4, showing a piece of work between the work positioning pins to be acted upon by the machine.

Figure 5 is a sectional view similar to the lower portion of Fig. 4, showing the staple carrying member moved down to depress the work positioning pins, and showing the staple driver moved down about one-half the length of its stroke within the member.

Figure 6 is a sectional view showing the parts shown in Fig. 5 in the final positions thereof at the completion of a staple setting operation.

Figure 7 is a top view, enlarged, of the staple clinching the work positioning pins and the supporting block therefor.

Figure 8 is an enlarged side view of a piece of work having a staple set thereon by the machine to surround and enclose the work.

Figure 9 is a view of a modified form of staple for use within the machine, and a modified form of magazine bar for receiving and guiding a row of the modified staples.

Referring to the drawings, 2 designates the body or supporting frame of the machine, which is secured upon a suitable table or support 5.

The frame 2 is provided with a laterally and forwardly extending arm 6 having a horizontal bore therein for the reception of a shaft 7. One end of the shaft 7 extends outwardly from the bore in the arm 6 and supports a block 8 which carries the staple clinching anvil 9. The shaft 7 may be turned within the bore in the arm 6 and it may be moved longitudinally therein for the purpose of adjusting the block 8 and the parts carried thereby with relation to other parts of the machine, and the shaft 7 and block 8 are held in different positions of adjustment by set screws 10 screwed into the arm 6 and engaging the shaft.

A member 11 is pivoted, at 12, on the frame 2. One side of the member 11 is grooved and forms a magazine 13 for a row of staples 14. The row of staples 14 is embraced and are adapted to slide on a guiding rib or bar 15 which extends longitudinally in the magazine 13 and is secured at its bottom to the member 11. The staples 14 are guided by the bar 15 to be moved forwardly thereon and into a staple guiding channel 16 which extends up and down transversely to the bar 15 and which is formed by the forward end wall of the bar 15 and by two blocks 17 and 18 which are suitably secured within an opening in the member 11 back of a front plate 19 which is secured to the member 11 by screws 20.

The lower end portions of the blocks 17 and 18 form a nose 21 which extends downwardly from the forward end of the member 11 and through which the channel 16 extends. The lower end of the channel 16 is open and the channel is adapted to be brought substantially into vertical alignment with the staple clinching anvil 9, when the forward portion of the member 11 is moved downwardly to the position shown in Figs. 5 and 6.

The row of staples 14 is fed forwardly on the guiding bar 15 toward and against the front wall 17 of the channel 16 by a suitable follower 22 which embraces and is slidably fitted to the bar 15, and which is urged for.

wardly by a spring 23 which is connected thereto and to the member 11 in the usual manner to urge the row of staples 14 toward and against the wall 24 of the channel 16.

5 The space between the front end of the bar 15 and the wall 24 is equal to or slightly in excess of the thickness of one staple.

The lower portion of a staple driving plate 25 is fitted to slide in the channel 16 toward 10 and from the anvil 9 and the lower end of the plate 25 is made concave in form as shown, for a purpose hereinafter explained. The upper end portion of the staple driver 25 is secured to the lower end portion of a bar 26 15 which is fitted to slide within an upwardly extending limb 27 on the forward end portion of the member 11.

During the staple setting operations hereinafter described, the bar 26 is moved down 20 and up to reciprocate the staple driver 25 within the channel 16; and, at each downward stroke of the driver 25, from the position shown in Fig. 4 to the position shown in Fig. 6, the lower end thereof engages the 25 foremost staple of the row 14 thereof which rests against the wall 24 and drives the staple downwardly through the channel 16.

The bar 26 is pivotally connected to the forward end of a lever 28 which is fulcrumed, 30 at 29, on the member 11 and which is pivotally connected to the upper end of an operating bar 30 which extends downwardly from the lever 28 and through suitable openings in the base of the frame 2 and table 5.

35 The forward end of the lever 28 is bifurcated and embraces the limb 27 of the member 11 and it is pivotally connected to the bar 26 by a pin 31 which extends through a slot or opening in the bar and through vertical slots 40 33 or openings in the sides of the limb 27.

The lever 28 is raised relatively to the member 11 to raise the bar 26 and staple driver 25 within the channel 16 by a spring 32 which is interposed between the top of the member 45 11 and the bottom of the lever 28 and which is retained in place by a post which projects upwardly from the member 11 and which is encircled by the lower portion of the spring.

From the foregoing description, it will be 50 understood that the lever 28 may be depressed relatively to the member 11 against the action of the spring 32 to actuate the staple driver 25 within the channel 16, and that, normally, the spring 32 holds the pivot pin 31 in contact 55 with the upper end walls of the slots 33, so that the lever 28 and member 11 may be lowered and raised as a unit by lowering and raising the operating bar 30.

When the lever 28 and member 11 are 60 raised to the position shown in Figs. 1 and 2, further upward movement thereof is prevented by the engagement of a projection 34 on the member 11 with a lug 35 on the frame 2.

In the normal position of the machine, as 65 shown in Figs. 1 and 2, the projection 34 is

held against the lug 35 by the action of a spring 36, one end of which is attached to the operating bar 30 and the other end of which is attached to the bottom of the table 5.

The bar 30 may be connected to a suitable 70 pedal for operating the machine or it may be moved downwardly by any suitable means to effect the operation of the machine.

When the machine is operated by moving the bar 30 downwardly, the initial downward movement thereof moves the lever 28 and member 11 downwardly as a unit until a projection 37 on the member 11 engages an adjustable stop screw 38 carried by a boss 39 on the frame 2, and prevents further downward movement of the member 11, whereupon the continued downward movement of the bar 30 moves the lever 28, bar 26 and staple driver 25 downwardly relatively to the member 11 and against the action of the interposed spring 32 to drive a staple down through the channel 16 and set the same with relation to the work being acted upon by the machine, as will be hereinafter described.

80 The staple clinching anvil 9 is suitably secured within a depression in the top of the block 8 and the top of the anvil is made concave in cross section, as shown in Figs. 4, 5 and 6, so as to provide a channel for the reception of the work to be acted upon by the machine, and so that the anvil will embrace the work when it is placed thereon. In Figs. 4, 5 and 6, I have shown a round piece of work, indicated at 40, upon and embraced by the anvil.

90 The channel formed by the concavity in the top of the anvil 9 extends forwardly and rearwardly beneath the staple guiding channel 16, and the concave top of the anvil is provided with two laterally adjacent grooves 41 95 which extend from side to side thereof, for receiving and guiding the legs of a staple during the clinching or setting thereof. These grooves 41 have entrance openings 42 which are located on the respective sides of the anvil and beneath and in registry with the legs of a staple when it is being moved downwardly within the channel 16, as shown in Fig. 5; and the grooves 41 follow the curvature of the concavity of the anvil and extend from their entrance openings 42, on the respective sides of a straight line connecting the openings, as clearly shown in Fig. 7, so that when the staple legs are forced into the grooves 41, the legs will be forced into lapsing, lateral relation by the walls of the grooves.

100 Slidably fitted within guiding openings in the block 8 are two parallel, vertically-extending, work-positioning parts or pins 43. These pins 43 are located on the respective sides of the anvil 9 in close proximity thereto, and the upper end portions of the pins, in the normal positions thereof, as shown in Figs. 1, 2, 3 and 4, extend above the top of 105 110 115 120 125

the anvil 9 and are adapted to receive the work 40 between them and direct it to and properly position it with respect to the anvil when the work is placed thereon. The work 40 may be a number of pieces of any material around which the staple is to be set for binding them together or it may be a single piece of material around which the staple is set for identification or other purposes.

The pins 43 have collars or flanges 44 formed thereon which slide in expanded portions 45 of the pin guiding openings in the block 8, and the pins 43 are maintained normally elevated, with their collars 44 bearing against the upper end walls of the expanded portions 45 of the pin guiding openings by springs 46 which encircle the pins 43 between the lower end walls of such expanded portions and the bottoms of the collars 44, as shown in Figs. 4 and 5. It will now be understood that the pins 43 may be depressed against the action of their springs 46 from the normal position of the pins, as shown in Figs. 3 and 4, to the depressed position thereof, as shown in Figs. 5 and 6; and that, thereafter, when the pins 43 are released, their springs 46 will elevate them to their normal position.

The inner sides of the work-positioning upper end portions of the pins 43 are provided with vertically-extending grooves 47 which receive and are fitted to lateral extensions 48 of the anvil 9. The entrance openings 42 of the staple-clinching grooves 41 of the anvil are located in the lateral extensions 48 of the anvil and also within the grooves 47 of the pins 43, so that when the pins 43 are elevated and while they are being depressed, the inner portions of the pins 43, at the sides of the grooves 47, will hold the sides of any work placed between the pins, within the space between the entrance openings 42 of the staple clinching grooves 41 to insure the straddling of the work by a staple whose legs are forced into the clinching grooves.

The top of the anvil 9 is made concave to receive and embrace the lower portion of the work placed thereon, and the bottom of the nose 21 having the staple guiding channel 16 therein, is made concave, as illustrated, to receive and embrace the upper portion of the work placed upon the anvil 9, when the nose 21 is moved downwardly thereto, as shown in Figs. 5 and 6.

The space between the legs of each staple acted upon by the machine is equal to or slightly in excess of the space between the work-positioning upper end portions of the pins 43 at the sides of the grooves 41 therein, so that the pins 43 will maintain the work, irrespective of its character, within a space which is not greater than the space between the staple legs.

The operation of the machine is as follows:

When the machine is in the normal position, as shown in Figs. 1 and 2, with the staple guiding nose 21 elevated above the tops of the work-positioning pins 43, the work which is to have the staple applied thereto, is placed between the pins 43 and upon the anvil 9. This done, the operating bar 30 is depressed by hand, foot or other power against the action of the spring 36. During the initial downward movement of the bar 30, it moves the lever 28 and member 11 downwardly as a unit until the nose 21 engages and depresses the pins 43, and until the further downward movement of the lever 28 and member 11 as a unit is stopped by the engagement of the concave bottom of the nose 21 with the top of the work 40 upon the anvil 9, the resistance of the spring 32 to movement of the lever 28 relatively to the member 11 being greater than the resistance of the springs 46 to the depression of the pins 43. After the engagement of the nose 21 with the work 40 upon the anvil stops the downward movement of the member 11, the continued downward movement of the operating bar 30 moves the lever 28 downwardly relatively to the member 11 and thereby moves the bar 26 downwardly and moves the staple driver 25 downwardly within the channel 16 from its position therein as shown in Figs. 2 and 4, to its position therein, as shown in Fig. 6; and, during this downward movement of the driver 25, the bottom thereof engages the top of the foremost staple 14 of the row thereof and drives it downwardly through the channel 16 and drives the legs of the staple into the clinching grooves 41 of the anvil 9 until the further downward movement of the staple is stopped by the crown thereof engaging the work upon the anvil. As the staple is thus driven downwardly, it embraces the work 40 upon the anvil and the legs of the staple are directed by the walls of the grooves 41 to pass beneath the work laterally of one another and inlapping relation to embrace the lower portion of the work so that the staple is clinched or set around the work in a manner to completely encircle it and form a band surrounding the same, as shown in Fig. 8.

When the staple 14, having a straight crown, is thus clinched or set around the work, the concave lower end of the staple driver 25 will bend the crown of the staple, more or less, to conform to the curvature of the work.

After the staple has been clinched or set around the work, the downward pressure on the operating part 30 is removed and the springs 32, 36 and 46 are permitted to raise or return the parts of the machine to the normal position for a succeeding staple setting operation, following the feeding of a

fresh staple into the channel 16 by the action of the spring 23.

If the vertical dimensions of the work placed between the pins 43 and upon the anvil 9 are sufficient to prevent the depression of the upper ends of the pins 43 down to the level of the top of the anvil 9, before the downward movement of the nose 21 is stopped by its engagement with the work, the grooves 47 in the pins 43 serve as additional guides for the staple legs as they pass through the space between the bottom of the channel 16 and the entrance openings 42 of the clinching grooves 41, while the pins 43 prevent the lateral expansion of the work into the paths of the downwardly moving staple legs.

If desired the crown of the staple may be shaped, where the staple is made, to conform to the shape of the work with which it is to be engaged, and the bottom of the staple driver 25 may be correspondingly shaped.

In Fig. 9 I have shown a staple with a rounded crown 50 to fit upon round work, and I have shown the staple straddling a similarly shaped guiding bar 51 for guiding the staples into the channel 16 of the machine.

I claim:

1. In a staple setting machine, the combination of a supporting frame, a staple clinching anvil, a member movable toward and from the anvil and having a concave work embracing part and staple guiding means, a staple driver movable in the member, means operable to move the member to move its work embracing part into engagement with work upon the anvil and thereafter operable to move the driver toward the anvil.

2. In a staple setting machine, the combination of a supporting frame, a staple clinching anvil, a member movable toward and from the anvil and provided with staple guiding means, a staple driver movable in the member, means operable to move the member to move its work embracing part into engagement with work upon the anvil and thereafter operable to move the driver toward the anvil and yieldable work-positioning parts on the respective sides of the anvil and adapted to be engaged and moved by said member when it is moved toward the anvil.

3. In a staple setting machine, the combination of a supporting frame, a staple clinching anvil, a member movable toward and from the anvil and having a concave work-embracing part and staple guiding means, a staple driver movable in the member, means operable to move the member to move its work embracing part into engagement with work upon the anvil and thereafter operable to move the driver toward the anvil, and yieldable work-positioning parts on the respective sides of the anvil and adapted to

be engaged and moved by said member when it is moved toward the anvil.

4. In a staple setting machine, the combination of a supporting frame; a concave, work-embracing, staple-clinching anvil; a member movable toward and from the anvil and having a concave work-embracing part and staple guiding means, a staple driver movable in the member, and means operable to move the member to move its work embracing part into engagement with work upon the anvil and thereafter operable to move the driver toward the anvil.

5. In a staple setting machine, the combination of a supporting frame, a concave, work-embracing, staple-clinching anvil; a member movable toward and from the anvil and provided with staple guiding means, a staple driver movable in the member, means operable to move the member to move its work embracing part into engagement with work upon the anvil and thereafter operable to move the driver toward the anvil, and yieldable work-positioning parts on the respective sides of the anvil and adapted to be engaged and moved by said member when it is moved toward the anvil.

6. In a staple setting machine, the combination of a supporting frame, a concave, work-embracing, staple-clinching anvil; a member movable toward and from the anvil and having a concave work-embracing part and staple and guiding means, a staple driver movable in the member, means operable to move the member to move its work embracing part into engagement with work upon the anvil and thereafter operable to move the driver toward the anvil, and yieldable work-positioning parts on the respective sides of the anvil and adapted to be engaged and moved by said member when it is moved toward the anvil.

7. In a staple setting machine, the combination of a supporting frame, an anvil having laterally adjacent grooves constructed to receive the legs of a staple and to direct them laterally out of alignment and into lapping relation, a member movable toward and from the anvil and having a concave work-embracing part and staple guiding means, a staple driver movable in the member, and means operable to move the member and the driver toward the anvil.

8. In a staple setting machine, the combination of a supporting frame, an anvil having laterally adjacent grooves constructed to receive the legs of a staple and to direct them laterally out of alignment and into lapping relation, a member movable toward and from the anvil and provided with staple guiding means, a staple driver movable in the member, means operable to move the member and the driver toward the anvil, and yieldable work-positioning parts on the respective sides of the anvil and adapted to be engaged

and moved by said member when it is moved toward the anvil.

9. In a staple setting machine, the combination of a supporting frame, an anvil having laterally adjacent grooves constructed to receive the legs of a staple and to direct them laterally out of alinement and into lapping relation, a member movable toward and from the anvil and having a concave work-embracing part and staple guiding means, a staple driver movable in the member, means operable to move the member and the driver toward the anvil, and yieldable work-positioning parts on the respective sides of the anvil and adapted to be engaged and moved by said member when it is moved toward the anvil.

10. In a staple setting machine, the combination of a supporting frame; a concave, work-embracing, staple-clinching anvil having laterally adjacent grooves constructed to receive the legs of a staple and to direct them laterally out of alinement and into lapping relation, a member movable toward and from the anvil and having a concave work-embracing part and staple guiding means, a staple driver movable in the member, and means operable to move the member and the driver toward the anvil.

11. In a staple setting machine, the combination of a supporting frame; a concave, work-embracing, staple-clinching anvil having laterally adjacent grooves and constructed to receive the legs of a staple and to direct them laterally out of alinement and into lapping relation, a member movable toward and from the anvil and provided with staple guiding means, a staple driver movable in the member, means operable to move the member and the driver toward the anvil, and yieldable work-positioning parts on the respective sides of the anvil and adapted to be engaged and moved by said member when it is moved toward the anvil.

12. In a staple setting machine, the combination of a supporting frame; a concave, work-embracing, staple-clinching anvil having laterally adjacent grooves constructed to receive the legs of a staple and to direct them laterally out of alinement and into lapping relation, a member movable toward and from the anvil and having a concave work-embracing part and staple guiding means, a staple driver movable in the member, means operable to move the member and the driver toward the anvil, and yieldable work-positioning parts on the respective sides of the anvil and adapted to be engaged and moved by said member when it is moved toward the anvil.

13. In a staple setting machine, the combination of a supporting frame; a concave, work-embracing, staple-clinching anvil having laterally adjacent grooves constructed to receive the legs of a staple and to direct them laterally out of alinement and into lapping relation, a member movable toward and from the anvil and having a concave work-embracing part and staple guiding means, a staple driver movable in the member, means operable to move the member and the driver toward the anvil, and yieldable work-positioning parts on the respective sides of the anvil and adapted to be engaged and moved by said member when it is moved toward the anvil.

14. In a staple setting machine, the combination of a supporting frame, a staple clinching anvil, a member movable toward and from the anvil and provided with staple guiding means, a staple driver movable in

the member, a part operable to move the member toward the anvil and thereafter to move the driver toward the anvil, yielding means interposed between said part and said member, work-positioning parts on the respective sides of the anvil and adapted to be engaged and moved by said member when it is moved toward the anvil, and yielding means opposing the movement of said positioning parts by said member, the first named yielding means having greater resisting power than the second named yielding means.

15. In a staple setting machine, the combination of a supporting frame, a staple clinching anvil, a member movable toward and from the anvil and provided with staple guiding means, a staple driver movable in the member, means operable to move the member and the driver toward the anvil, vertically-movable work-positioning pins on the respective sides of the anvil and slidable in a part supported by said frame, and springs maintaining said pins normally elevated and against which the pins may be depressed by said member.

16. In a staple setting machine, the combination of a supporting frame, a staple clinching anvil, a member movable toward and from the anvil and provided with staple guiding means, a staple driver movable in the member, means operable to move the member and the driver toward the anvil, a shaft adjustably held in said frame and provided with a block which supports said anvil and yieldable work-positioning parts carried by said block on the respective sides of the anvil and adapted to be engaged and moved by said member when it is moved toward the anvil.

17. In a staple setting machine, the combination of a supporting frame, a staple clinching anvil, a member movable toward and from the anvil and provided with staple guiding means, a staple driver movable in the member, means operable to move the member and the driver toward the anvil, vertically-movable, work-positioning pins on the respective sides of the anvil and slidable in said block, and springs maintaining said pins normally elevated and against which the pins may be depressed by said member.

In testimony whereof I affix my signature.

HARRY E. HICKS.
